UNITED STATES PATENT OFFICE.

JOHN JACOB SCHAIRER, OF CLINT, TEXAS.

SASH LOCK AND LIFT.

SPECIFICATION forming part of Letters Patent No. 684,873, dated October 22, 1901.

Application filed October 16, 1899. Serial No. 733,782. (No model.)

To all whom it may concern:

Be it known that I, JOHN JACOB SCHAIRER, a citizen of the United States, residing at Clint, in the county of El Paso and State of Texas, have invented certain new and useful Improvements in Window-Sash Locks and Operators; and I do hereby declare the following to be a full, clear, and exact description of the invention, such as will enable others skilled in the art to which it appertains to make and use the same.

My invention relates to improvements in devices for operating window-sashes, and especially provides an improved means for operating the upper sash and locking the same securely in any desired position with respect to the lower sash, thus obviating the necessity for reaching up to the upper sash when it is desired to raise or lower the same or to lock it in open position for the purpose of ventilation.

Although I have incidentally mentioned a shade carried by the upper sash, I do not claim this as a part of my invention.

My invention will be understood by reference to the accompanying drawings, wherein the same parts are indicated by the same letters throughout the several views.

Figure 1 represents a fragmentary view in perspective with my window-sash locked and the operator applied to a window. Fig. 2 represents a perspective view, parts being broken away, of the device detached from the window. Fig. 3 represents a perspective view of the shade-bracket which is used in conjunction with the bracket forming a part of the sash-operating device shown in Fig. 2. Fig. 4 represents a view, partly in section, showing means locking the sliding connection between the two rods of the device; and Fig. 5 is a view, partly in section and partly in elevation, showing the automatic catch for locking the lower sash when closed.

A represents a standard having a base A⁰, provided with screw-openings a⁰, by means of which the said standard may be secured to the window-sash. This standard A is provided with an extension A', preferably offset to one side, as shown in Fig. 2, and provided with a circular opening a', the said extension being for the support of one end of the window-shade, (shown at S in Fig. 1.) The

standard A is secured to the upper portion of the upper sash T, preferably at or near the right-hand upper corner thereof, as shown in Fig. 1. The standard A is preferably provided with an enlargement A² of an ornamental nature, to which is rigidly secured the upper end of a vertical depending rod B.

C represents a standard or bracket which is secured to the lower sash, preferably at or near its bottom right-hand corner, as shown in Fig. 1, and to an ornamental enlargement C² upon the laterally-extending arm C' of said bracket is rigidly connected a vertical upwardly-extending rod D. The rod D is of such length as to extend to the top edge of the lower sash and is connected at its upper end rigidly to an ornamental bracket or standard D², which is provided with a perforated stem D', arranged to be secured upon the top edge of the lower sash T'. The bracket D² is provided with a guide D³, through which passes the upper sash or rod B. This upper sash-rod should be slightly longer than the height of the upper sash, and it is rigidly connected at its lower end to a block B², provided with a guide B³, through which passes the rod D. In this manner the two rods B and D may move longitudinally with respect to each other by moving through the guides D³ and B³, respectively. The guide-block B² may be clamped with respect to the rod D by means of a screw-plug E, operated by a handle E', so that when it is desired to lock the two sashes with respect to each other this is accomplished by simply turning the handle E', which operates the locking-pin E.

The bracket C carries a gravity-hook F, which is arranged to engage with a catch F', secured to the window-sill, when the lower sash is fully down, the action of the said gravity-hook F being automatic in its engagement with the catch F'. The said hook may be readily disengaged for raising the lower sash by lifting it from engagement with the catch F'. When the lower sash is thus locked by means of the hook F, it will be seen that the upper sash may be securely locked against movement in the frame by means of the handle E', above referred to, which prevents the rods B and D moving with respect to each other.

H represents a standard of a form some-

what similar to the standard A, above described, and intended to be similarly attached to the window-sash at the opposite upper corner therefrom. This standard is provided 5 with an offset portion H', having an angular open slot h' in its end for the reception of the spring end of an automatic spring shade-roller.

From the foregoing it will be seen that the 10 shade-roller may be mounted in the standards A and H in the same manner as it is common to mount a shade-roller upon the frame of a window and that the mounting of the same upon the sash instead of upon the frame 15 of the window has the advantage that the upper sash when raised and lowered carries with it the shade and renders it possible to provide ventilation at the top of the sash and at the same time allow for the use of the 20 shade to screen out excessive light without the shade interfering with the ventilation and without injury to the shade.

The length of the standards A and H is sufficient to allow the shade to fall inside of the 25 lower sash without interfering therewith.

I do not wish to limit myself to the precise details herein shown and described, as many modifications might be made which could be used without departing from the spirit of my 30 invention.

The many advantages of my device will be apparent to any practical mind.

Having thus described my invention, what I claim, and desire to secure by Letters Patent of the United States, is—

35

1. In a window-sash fastener, the combination with the upper and lower sash, of a rod rigidly secured to said lower sash, a second rod rigidly secured to and movable with said upper sash and adjustably secured to said 40 first rod, substantially as described.

2. In a window-sash fastener, the combination with the upper and lower sash, of a bracket secured to the lower end of said lower sash, an automatic locking device secured in 45 the base of said bracket, a second bracket secured to the top portion of said lower sash, a rod rigidly supported between said upper and lower brackets, an adjustable slide mounted on said rod, a second rod secured 50 to and movable with said upper sash and at its lower end secured to said adjustable slide, substantially as described.

In testimony whereof I affix my signature in presence of two witnesses.

JOHN JACOB SCHAIRER.
